Application April 10, 1947, Serial No. 740,649

11 Claims. (Cl. 179—171.5)

1

This invention relates to improvements in the means for modulating the amplitude of alternating current voltages in a manner which will allow the modulated voltage to retain its sinusoidal wave-form without distortion. Ordinarily, amplitude modulation is accomplished by an element acting as a switch, which, being operated by the modulating voltage and operating upon the carrier voltage, converts the constant amplitude of the carrier voltage to a voltage whose amplitude varies at a predetermined rate.

In most applications, it is relatively unimportant as to whether or not the carrier is distorted in the process of being modulated, since the intelligence is contained only in the modulation frequency and demodulation will yield the intelligence back again; however, in applications where the carrier frequency is to be used as modulated, clipping, introduction of harmonics, or any other form of distortion caused by the switch action of the modulator upon the carrier may give rise to undesirable effects, hence the need for a modulator which will permit the carrier to retain its undistorted sinusoidal wave-form.

Accordingly, this invention provides a means whereby a sinusoidal alternating voltage of one frequency may be made to vary its amplitude at the rate of a second, lower frequency, voltage, and retain its sinusoidal character. Furthermore, the means provided is such, that the amplitude of the output voltage, as modulated, is a linear function of the amplitude of the modulating voltage.

These and other features of the invention will become apparent in the course of the following description, it being understood, however, that the description, specification and drawings are intended to illustrate rather than define and limit the scope of the invention, reference being made to the appended claims for that purpose.

In the drawings:

Fig. 1 is a diagrammatic view of one form of the sinusoidal modulator;

Fig. 2 is a diagrammatic view of another form of the sinusoidal modulator;

Fig. 3 is a perspective view of the transformer therein employed;

Fig. 4 is a transverse section on the line 4—4 of Fig. 3;

Fig. 5 is a plot of the amplitude versus time of a voltage used as a carrier;

Fig. 6 is a plot of the amplitude versus time of a voltage used as a modulating frequency; and

Fig. 7 is a plot of the amplitude versus time of the resultant modulated carrier.

Referring to the drawings, a sinusoidal voltage

2

⁵ _{E₁} as shown in Fig. 5 is to be modulated with a voltage _{E₂} as shown in Fig. 6, the resultant modulated voltage to retain the sinusoidal character of the initial voltage, as shown in Fig. 7.

¹⁰ The action of the modulator may be analyzed from the behavior of the elements shown in Fig. 1. The modulator consists of a bridge having as ratio arms, elements 1 and 2, a comparison arm element 3 and an unknown arm element 4. If an alternating voltage is applied between terminals ¹⁵ 5 and 6, no voltage will appear at the terminals 7 and 8 when the resistance of arm 1 equals the resistance of arm 2 and the resistance of arm 3 equals the resistance of arm 4. If the resistance of three of the four arms is made identical but the resistance of the fourth arm is made larger, a voltage will appear between terminals 7 and 8 having a magnitude determined by and proportional to the degree of unbalance, and a phase corresponding to the phase of the voltage between terminals 5 and 6. If the fourth arm is made smaller, a voltage will appear between terminals 7 and 8 having a magnitude determined by and proportional to the degree of unbalance, and a phase opposed to the voltage between terminals ²⁰ 5 and 6.

²⁵ The vacuum tube 9 which constitutes the fourth bridge arm is not a linear resistor at best, and must be operated with proper electrode potentials in order that it behave like a resistor and not like a non-linear conductor or rectifier. To that end, a source of direct current 10, an isolation choke 11 to prevent the alternating current in the bridge from having a shunt path other than the bridge proper, a bias resistor 12 to set the operating point of the tube, and a by-pass capacitor 13 to eliminate the effect of resistor 12 on the alternating current circuit, are all employed to make the use of the vacuum tube as a resistor a possibility.

³⁰ Since the comparison arm of the bridge is a similar vacuum tube 14 and not a resistor, similar methods must be employed to make its use permissible. Therefore, it, too, is supplied from the direct current source 9 through the isolation choke 10, and furnished with a bias resistor 15 and a by-pass condenser 16. Its grid 17, however, is grounded so that its resistance may remain fixed.

³⁵ The potential of the direct current source must be maintained higher than the peak carrier voltage applied to terminals 5 and 6. The plate voltage of the vacuum tubes as applied to the anodes 9 and 14 will be the instantaneous sum of the battery voltage, plus the applied carrier voltage which is applied to the terminals 5 and 6, and

will never be negative if the negative peak of the carrier does not exceed the battery voltage; thus the plate resistance of the vacuum tubes which is in part dependent upon plate voltage, will always be some real value, not infinity (which it would become if the plate voltage were permitted to become negative). The two tubes 16 and 17 will always have comparable plate resistances and will function as resistors in the bridge circuit.

By changing the potential of the grid 18 of tube 9 by applying the modulating voltage E_2 (Fig. 6), we may change its effective resistance in the bridge circuit. This grid is negative with respect to cathode 19 by virtue of the direct current I. R. drop in the bias resistor 12 and, as long as the voltage applied to grid 18 does not exceed the bias potential, the tube will operate Class A, will draw no grid current, and will have the effect of a linear change in the plate resistance of vacuum tube 9. If the grid is made more positive but does not exceed the bias voltage of the vacuum tube 9, the plate resistance thereof will go down, thus unbalancing the bridge, and a voltage will appear across terminals 7 and 8 and will increase in magnitude and have a phase corresponding to the voltage across terminals 5 and 6 and be proportional to the amplitude of the modulating voltage E_2 . If the voltage is made more negative but does not exceed the value of plate current cutoff for the vacuum tube 9, the plate resistance will go up, unbalancing the bridge and a voltage will appear across terminals 7 and 8 and will have a phase opposed to the voltage across terminals 5 and 6 and be proportional to the magnitude of the modulating voltage E_2 .

The output voltage, however, has its origin in the carrier voltage and no factors enter to distort its wave-form. Its magnitude and phase, however, are now determined by the applied grid voltage and the carrier is, therefore, modulated with complete linearity and without distortion.

Another form of the invention is shown in Fig. 2. This application consists of two circuits such as are shown in Fig. 1 and hereinbefore described with resistors 1 and 2 being omitted from both and in their place inductances substituted therefor, combined into a single transformer, with the output circuit being inductively coupled thereto, as shown by transformer 29.

As shown in Fig. 2, the carrier voltage E_1 is introduced into transformer 21 across the terminals 20a and 20b thereof. The voltage appearing at the secondary 22 of transformer 21 will consist of two voltages as measured between terminals 23 and 24 and between terminals 23 and 25, which voltages are out of phase. Terminal 23 is maintained at ground potential for alternating current by means of capacitor 26. The voltage between terminals 23 and 24 of transformer 21 is applied to center tap 27 of winding 28 of transformer 29; the voltage between terminals 23 and 25 of transformer 21 is applied to center tap 30 of winding 31 of transformer 29. Thus the terminals 32 and 33 are at the same alternating potential, and terminals 34 and 35 are at the same alternating potential but opposite in phase to terminals 32 and 33.

By means of transformer 36, rectifier tube 37 and the filter network 38, a direct current voltage is made available and applied to terminal 23 of transformer 21. The circuits will function without this direct current voltage and it is not essential to the operation of the modulator unless an extended linear range is required. Elements 36, 37 and 38 may, therefore, be completely omitted.

ted. However, they are shown in the drawing and included in the specification because of the extended range of operation permitted by their inclusion. The current flow due to this direct current voltage divides and flows in opposite directions, that is to say, from terminals 23 to 24 and from terminals 23 to 25 so that any components due to this current flow has no effect on the alternating current characteristic of the circuit due to saturation of the transformer core.

Terminals 24 and 25 of transformer 21 are at the same direct current potential with respect to ground and because of the connections between terminals 24 and 27 and between terminals 25 and 30, terminals 32, 33, 34 and 35 are at the same direct current potential with respect to ground. Terminal 32 is connected to anode 39 of triode 49 of the twin triodes comprising vacuum tube 41 and terminal 33 is connected to anode 42 of triode 43 of vacuum tube 40 (a twin triode being shown for convenience and separate tubes of any nature comprising three or more elements being applicable) thus energizing the two triode section anodes with similar direct current potentials. The cathodes 44 and 45 of said triodes are connected together through a resistor 46 and returned to ground through a variable tap 47 thereon in series with resistor 48 so that the direct current in the two sections of the tube may be made identical. In the same way, terminal 35 is connected to anode 49 of triode 50 of vacuum tube 51, terminal 34 is connected to anode 52 of triode 53 of vacuum tube 51, thus energizing both triode section anodes of vacuum tube 51 with similar direct current potentials. The cathodes 54 and 55 of said triodes are connected together through resistor 56 and returned to ground through variable tap 57 thereon in series with resistor 48 so that the current in these two tubes may be made identical. Resistor 48 is connected in circuit so that the I. R. drop of the direct current therein affords the bias voltage necessary to set the operating point of all of the triodes. Grids 58 and 59 of vacuum tubes 40 and 50 are connected directly to ground. The remaining grids 60 and 61 are connected in parallel with resistor 62, which is included to provide a direct current return if the driving source should fail to provide one, and are connected to the source of the modulating voltage E_2 (Fig. 6). When the modulating voltage E_2 is zero all four triodes 49, 43, 50 and 53 draw equal plate currents and since the plate currents for vacuum tube 41 flows from terminal 30 to 32 and terminal 30 to 33 in winding 51 of transformer 29, that is to say, in opposite directions from the center tap thereof, and the plate currents for vacuum tube 51 flows from terminal 27 to 34 and from 27 to 35 in winding 28 of transformer 29, that is to say, in opposite directions from the center tap thereof, the direct current components cancel and produce no effect in the transformer.

When a carrier voltage E_1 such as is shown in Fig. 5 is impressed between terminals 20a and 20b of transformer 21, the potentials as they exist between terminals 23 and 24, and between 23 and 25, change so that their instantaneous value is equal to the direct current voltage plus the alternating current voltage. This voltage is never permitted to become negative, but varies about some positive point at the carrier frequency.

Because of the connections heretofore outlined for the direct currents, the anode voltages will vary in the same way, the anodes 39 and 42 being made more positive while the anodes 49 and 52

are being made more negative, and on the remaining half cycle, the anodes 39 and 42 being made more negative while anodes 49 and 52 are being made more positive.

The individual tube currents, however, still balance in windings 28 and 31 of transformer 29 and no voltage will therefore be induced in winding 63 thereof.

If a modulating voltage E_2 such as shown in Fig. 6 is introduced across resistor 57 and is positive, the grids 60 and 61 of sections 43 and 53 of vacuum tubes 41 and 51 are caused to go positive. The triodes 43 and 53 will therefore draw larger plate currents, thus unbalancing the division of currents at terminal 27 and 30, larger currents flowing from 27 to 34 and from 30 to 33 and smaller currents flowing from 28 to 35 and from 31 to 32. The magnetic effect of the direct current flow will continue to be zero and cause no saturation because the magnetic effect of the current flow from 30 to 33 opposes the magnetic effect of the current flow from 27 to 34, and the magnetic effect of the current flow from 30 to 32 opposes the magnetic effect of the current flow from 27 to 35. The magnetic effect of the alternating currents, however, will not be zero but will induce a voltage in winding 63 of transformer 29. When the alternating current voltage at terminal 30 is positive the current in the direction from 30 to 33 will exceed the current in the direction from 27 to 34 and on the remaining half cycle when the alternating current voltage at 27 is positive, the current will flow in the direction from 27 to 34 and will exceed the current flow from 30 to 33 thus causing the alternating current to flow first from 30 to 33 and then from 27 to 34, which currents will induce a voltage in winding 63 whose magnitude is determined by the voltage impressed upon resistor 62 and by the amount by which the grids 60 and 61 are made positive. The voltage in winding 63 will have a phase which corresponds to the phase of the voltage applied to terminals 20a and 20b of transformer 21. If the voltage across resistor 62 is negative, the direct current flowing from 30 to 33 and from 27 to 34 will be decreased, the direct current flowing from 30 to 32 and from 27 to 35 will remain the same and since the magnetic effect of the direct current from 30 to 33 opposes that from 27 to 34 and the magnetic effect of the direct current from 30 to 32 opposes that from 27 to 35 the net result caused thereby will be zero.

The alternating currents, however, will again not be zero for when the alternating current at terminal 30 is positive, the current flow in the direction from 31 to 32 will exceed the current flow in the direction from 27 to 35, and on the remaining half cycle when the alternating current on the terminal 27 is positive the current flow from terminal 27 to 35 will exceed the current flow from 30 to 32 thus causing an alternating current to flow first from terminal 30 to 32 and then from terminal 27 to 35 which will induce a voltage in the secondary 63 of transformer 29 which is determined in magnitude by the degree to which the grids 60 and 61 are made negative and is opposed in phase to the voltage applied to the terminals 20a and 20b of the transformer 21.

Thus, at any instant, the magnitude of the modulating voltage E_2 determines the output voltage across winding 63 of transformer 29 impressing upon it a modulation envelope and yet

permitting it to retain its sinusoidal characteristics.

It is imperative for the operation of this form of the device that the transformer 29 be constructed with very close coupling between all of its several windings so that the leakage reactance be held to a minimum and the transfer of energy between its several windings be a maximum. A recommended form of its construction is illustrated in Fig. 3 which is a perspective view of the transformer and in Fig. 4 which is a cross section thereof on a line 4-4 wherein it is shown that the windings 28 and 31 of the transformer 29 are placed side-by-side on the center leg 59 of a three-legged core consisting of the laminations 64 and winding 63 fitted so as to enclose the windings 28 and 31. The laminations 64 must have interleaved stacking 65 and the winding must fill as much as possible of the available space in the core.

Other means such as multi-element tubes having multiple grid structures might be used to eliminate the transformer 29 as is apparent to anyone skilled in the art, or other variations may suggest themselves for the accomplishment of the same purpose.

What is claimed is:

1. A modulator of the character described comprising means for separating a carrier frequency voltage of constant amplitude into out of phase components and for superimposing said components of carrier frequency voltage upon a direct current voltage, a plurality of vacuum tubes, transformer means having a plurality of mutually coupled windings to utilize the separated components of carrier frequency voltage and direct current voltage for energizing the anodes of said vacuum tubes in pairs, means to vary the conductance of said vacuum tubes for energizing, in pairs, those grids thereof which are not already paired together with a modulating voltage, the remaining grids being grounded, the second named means co-acting with the variations in conductance of said vacuum tubes to vary the current flow in said vacuum tubes due to said components of carrier frequency voltage and to direct current voltage, and to mutually couple the variations in conductance of carrier frequency voltage to an output circuit.
2. A modulator of the character described comprising means for separating a carrier frequency voltage of constant amplitude into out of phase components and for superimposing said components of carrier frequency voltage upon a direct current voltage, a plurality of vacuum tubes, means to utilize the separated components of carrier frequency voltage and direct current voltage for energizing the anodes of said vacuum tubes in pairs, means to vary the conductance of said vacuum tubes by energizing, in pairs, those grids thereof which are not already paired together with a modulating voltage, the second named means co-acting with said variation in conductance of said vacuum tubes to vary the magnitude of the current flow in said vacuum tubes due to components of carrier frequency voltage, to direct current and to couple the variations in magnitude due to carrier frequency alone to an output circuit.
3. A modulator of the character described comprising means for separating a carrier frequency voltage of constant amplitude into out of phase components, a plurality of vacuum tubes, transformer means having a plurality of mutually coupled windings to utilize the separated com-

ponents of carrier frequency voltage to energize the anodes of said vacuum tubes in pairs, each pair associated with one winding, means to vary the conductance of said vacuum tubes by energizing, as a pair, two grids thereof which are not already paired with a modulating voltage, the remaining grids being grounded, the second named transformer means co-acting with said variation in conductance of said vacuum tubes to vary the current flow in said vacuum tubes due to said components of carrier frequency voltage and to mutually couple the variations thus produced to an output circuit.

4. A modulator of the character described comprising mutually coupled means for separating the carrier frequency voltage of constant amplitude into out of phase components, a plurality of vacuum tubes, means to utilize the components of carrier frequency voltage to energize the anodes of said vacuum tubes in pairs, means to vary the conductance of said vacuum tubes by energizing, in pairs, those grids thereof which are not already paired together with a modulating voltage, the second named means co-acting with said variation in conductance of said vacuum tubes to vary the magnitude of the current flow in said vacuum tubes due to said components of carrier frequency voltage and to couple the variations in magnitude thus produced to an output circuit.

5. A modulator of the character described comprising mutually coupled means for separating the carrier frequency voltage of constant amplitude into out of phase components, a plurality of vacuum tubes, a transformer having three or more separate windings, circuit means coupling the first named means to said vacuum tubes to energize the anodes thereof in pairs with the separated components of carrier frequency voltage, means to vary the conductance of said vacuum tubes by energizing those grids thereof which are not already paired together with a modulating voltage, said transformer co-acting with the variation in conductance of said vacuum tubes to vary the magnitude of current flow due to said components of said carrier frequency voltage and coupling the variation in magnitude thus produced to an output circuit.

6. A modulator of the character described comprising mutually coupled means for separating the carrier frequency voltage of constant amplitude into out of phase components and for superimposing said components of said carrier frequency voltage upon a direct current voltage, a plurality of vacuum tubes, a transformer having three or more separate windings, circuit means coupling the first named means to said vacuum tubes to energize the anodes thereof in pairs with the separated components of carrier frequency voltage, means to vary the conductance of said vacuum tubes by energizing those grids thereof which are not already paired together with a modulating voltage, said transformer co-acting with the variation in conductance of said vacuum tubes to vary the magnitude of current flow due to said components of said carrier frequency voltage and coupling the variation in magnitude thus produced to an output circuit.

7. A modulator of the character described, comprising a pair of vacuum tubes, each having an anode, a cathode, and one or more control electrodes, a pair of impedances, a pair of carrier input terminals and a pair of carrier output terminals, said vacuum tubes and impedances being arranged, with respect to said carrier in-

put terminals, so that said vacuum tubes are in series, and said impedances are in series, and so that said vacuum tubes, in series, are in parallel with said impedances in series, the vacuum tubes and impedances being further arranged so that, with respect to said carrier output terminals, each of said vacuum tubes is in series with one of said impedances, and so that one of said vacuum tubes in series with one of said impedances is

10 in parallel with the other of said vacuum tubes in series with the other of said impedances, a source of direct current in parallel with said carrier output terminals, means to prevent the carrier output from flowing in the direct current source, 15 means for introducing a modulating voltage, and means for varying the conductance of said vacuum tubes with said modulating voltage.

8. A modulator of the character described, comprising a pair of vacuum tubes, each having an anode, cathode, and one or more control electrodes, a pair of resistors, a pair of carrier input terminals and a pair of carrier output terminals, said vacuum tubes and resistors being arranged, with respect to said carrier input terminals, so that said vacuum tubes are in series, and said resistors are in series, and so that said vacuum tubes in series are in parallel with said resistors in series, the vacuum tubes and resistors being further arranged so that, with respect to said carrier output terminals, each of said vacuum tubes is in series with one of said resistors and in parallel with the other of said vacuum tubes in series with the other of said resistors, a source of direct current in parallel with said carrier output terminals, means to prevent the carrier output from flowing in the direct current source, means for introducing a modulating voltage, and means for varying the conductance of said vacuum tubes with said modulating voltage.

40 9. A modulator of the character described, comprising a pair of vacuum tubes each having an anode, cathode, and one or more control electrodes, a pair of inductors, a pair of carrier input terminals and a pair of carrier output terminals, said vacuum tubes and inductors being arranged, with respect to said carrier input terminals, so that said vacuum tubes are in series, and said inductors are in series, and so that said vacuum tubes in series are in parallel with said inductors in series, the vacuum tubes and inductors being further arranged so that, with respect to said carrier output terminals, each of said vacuum tubes is in series with one of said inductors and so that one of said vacuum tubes in series with one of said inductors is in parallel with the other of said vacuum tubes in series with the other of said inductors, a source of direct current in parallel with said carrier output terminals, means to prevent the carrier output from flowing in the direct current source, means for introducing a modulating voltage and means for varying the conductance of said vacuum tubes with said modulating voltage.

65 10. A modulator of the character described, comprising a pair of vacuum tubes, each having an anode, cathode and one or more control electrodes, and a transformer having two or more mutually coupled windings, one of which is center tapped, a pair of carrier input terminals and a pair of carrier output terminals, said vacuum tubes and transformer being arranged so that with respect to the carrier input terminals the center tapped winding is in parallel with the aforesaid pair of vacuum tubes which are in

series, a direct current source, said vacuum tubes and center tapped winding of said transformer being further arranged so that with respect to the direct current source, one-half of said center tapped winding, in series with one of said vacuum tubes, is in parallel with the remaining half of the said center tapped winding, in series with the remaining vacuum tube, means for introducing a modulating voltage, means for varying the conductance of said vacuum tubes in accordance with said modulating voltage and means comprising the remaining, untapped winding of said transformer to keep the carrier output from flowing in the direct current source.

11. A modulator of the character described, comprising a plurality of vacuum tubes and a plurality of impedances which vacuum tubes and impedances are arranged with respect to the input terminals of a carrier voltage so that the impedances are in series, and are in parallel, in pairs, with said vacuum tubes which are in series, said vacuum tubes and impedances being further

5
10

arranged so that with respect to the output terminals of a modulated carrier, each of said vacuum tubes, in series with one of said impedances, is in parallel with the other of said vacuum tubes which, individually, are in series with the other of said impedances, a source of direct current in parallel with said vacuum tube and impedance elements as arranged in series, and means to vary the conductance of said vacuum tubes with a modulating voltage.
